UNITED STATES PATENT OFFICE.

WILLIAM F. HUTCHINSON, OF NYACK, NEW YORK, ASSIGNOR TO SARNIA MATCH COMPANY,
OF SARNIA, ONTARIO, CANADA, A CORPORATION OF CANADA.

MATCH-MACHINE.

No. 866,649.

Specification of Letters Patent.

Patented Sept. 24, 1907.

Application filed September 14, 1906. Serial No. 334,608.

To all whom it may concern:

Be it known that I, WILLIAM F. HUTCHINSON, of Nyack, Rockland county, and State of New York, have invented a new and Improved Match-Machine, of 5 which the following is a full, clear, and exact description.

My invention relates to improvements in match machines, and especially to that type of match machines known as continuous machines, and in which 10 the match holding frames or carriers are fed opposite mechanism which inserts splints therein, the carriers then serving to convey the splints to points where they are dipped in the various compositions. In machines of this class there is considerable difficulty in keeping 15 the carriers absolutely steady so that the splints will be correctly inserted.

The object of my invention is to produce a steady device which will hold the frames in a very rigid manner while they are passing opposite the mechanism for 20 inserting match splints therein.

With these ends in view, my invention consists of certain features of construction and combinations of parts which will be hereinafter described and claimed.

Reference is to be had to the accompanying drawing 25 forming a part of this specification, in which similar reference characters indicate corresponding parts in all the views.

Figure 1 is a front elevation with the carriers in section, of a machine showing my improvement, and Fig. 2 30 is a detail perspective view on an enlarged scale, of the mechanism for steadyng the carrier.

The machine illustrated has a suitable frame 10, and extending longitudinally through the machine are the 35 guide tracks 11 on which run the carrier frames 12, which pass through in contact with each other, and may

be of any length, or may be hinged together if preferred. As illustrated these frames comprise the side pieces 13, the cross rods 14, and the longitudinal centrally disposed stiffening ribs 15. I have shown enough of the rest of the machine merely to illustrate the use of the 40 carriers. The machine has a driving shaft 17, which through suitable mechanism at 18 moves the cutting-off knife 19, which severs strips of veneer, and splints are pushed down into the carrier between the rods 14 by the plungers 20. The plungers are worked from the 45 mechanism 21, and the frames are fed by the gear mechanism shown at 22.

I have not attempted to show the working of the machine, and have shown it only in a general way because my particular guiding mechanism is not limited to any 50 special form of splint cutting means. It will be observed that as the frames 12 are fed through the machine they will be held perfectly steady, as the rib 15 fits snugly in the slot 16^a of the central guide 16, and this extends longitudinally through the machine parallel 55 with the guide tracks 11, and preferably at a point about midway between the tracks.

Having thus fully described my invention, I claim as new and desire to secure by Letters Patent:

1. In a match machine, the combination with the carriers or frames arranged to move longitudinally through the machine, of a slotted guide, and a rib on the face of the frames or carriers running in the said slotted guide.

2. In a match machine, the combination with the splint carrier or frame, of a stationary slotted guide arranged 65 parallel with the movement of the frame, and a rib located between the two sides of the frame and running in the slotted guide.

WILLIAM F. HUTCHINSON.
